UNITED STATES PATENT OFFICE.

HENRY G. SWEENEY, OF CHICAGO, ILLINOIS, ASSIGNOR TO FRANK G. KAMMERER, OF CHICAGO, ILLINOIS.

VENDING MECHANISM.

SPECIFICATION forming part of Letters Patent No. 740,202, dated September 29, 1903.

Application filed November 21, 1902. Serial No. 132,207. (No model.)

To all whom it may concern:

Be it known that I, HENRY G. SWEENEY, of Chicago, in the county of Cook and State of Illinois, have invented certain new and useful 5 Improvements in Vending Mechanism; and I do hereby declare that the following is a full, clear, and exact description thereof, reference being had to the accompanying drawings, and to the letters of reference marked 10 thereon, which form a part of this specification.

This invention relates to improvements in vending-machines and like devices.

The invention consists in the matters hereinafter described, and pointed out in the appended claims.

In the accompanying drawings, illustrating my invention, Figure 1 is a perspective view of an apparatus embodying the invention. Fig. 2 is a plan view of the same. Fig. 3 is 20 a vertical section taken on line 3 3 of Fig. 2. Fig. 4 is a perspective view of a modified form of device embodying the main feature of my invention. Fig. 5 is a longitudinal section of the valve shown in Fig. 4. Figs. 6 and 7 25 are cross-sections of the valve shown in Fig. 5.

As shown in said drawings, A indicates a vertical plate, which may constitute the front wall or part of the front wall of a casing or housing containing a vending apparatus, and 30 B a horizontal plate on which the principal operative parts of the device are mounted.

C indicates a detent-lever which is arranged to swing in a vertical plane and which is adapted to be operated by the weight of a 35 coin and constitutes part of any suitable coin-controlled device which may be used in connection with the vending device illustrated. Said detent-lever C is mounted on a horizontal frame-arm D on the plate B and is shown 40 as supported on a pivot E, the ends of which are secured in parallel lugs or standards d d, which rise from the frame-arm D. The detent-lever C at the end thereof opposite that on which the coin acts is extended downwardly to form a locking arm or detent C', 45 which passes through a slot d', formed in the supporting-arm D.

F indicates an actuating-plate located beneath the stationary arm D and adapted to 50 swing in a horizontal plane, said plate being mounted on a vertical pivot f, herein shown

as passing at its upper end through the arm D and at its lower end into the plate B. The plate F is provided at its free edge beneath the end of the arm D, which contains the slot 55 or notch d', with two locking-notches f' f'. Said plate F is adapted to be swung or oscillated about its pivot f, so as to bring either one of the notches f' f' beneath the notch d' and in position to be engaged by the detent-arm C' when the end of said lever C, carrying said arm, is depressed. The detent-lever C is so weighted or balanced at its ends that when there is no coin in position to act thereon the end of said detent-lever C, on which the 65 detent-arm C' is attached, will remain depressed by gravity and in position for engagement with one of the notches f' f' in the plate F. When, however, a coin rests on the rear end of the detent-lever, the lever will be 70 moved by the weight of the coin, so that the detent-arm C' on the opposite end of said lever C will be lifted above and free from the plate F. Said lever is shown as provided adjacent to the detent-arm C' with a horizontal 75 rod E², on which is placed an adjustable weight E³.

H H are two upright levers connected at their upper ends with opposite extending laterally-directed actuating-arms F' F' on the plate 80 F and pivoted at their lower ends to suitable stationary supports, herein shown as having the form of horizontal arms h h, attached to the front plate A. Attached to said levers H are rods I, having at their ends push-buttons or finger-pieces I', which extend through holes or apertures in the front plate A. The said push-buttons I' I' through their connection with the plate F will be moved inwardly or outwardly in the plate A as the said plate 90 F is oscillated. It follows that when said plate is at one limit of its oscillatory movement one of the push-buttons will be at its outward and the other at its inward position, and it follows that if the finger be pressed on the 95 push-button which is at the outward limit of its movement the plate will be moved or shifted through the action of the rod I and the lever H, so as to swing rearwardly or inwardly the actuating-arm of the plate F, with which the actuated push-button is connected, and at the same time to swing forwardly the op-

posite side of the plate, and thus carry the other or opposite button to its outward position. It follows that one or the other of the two push-buttons will always be at the outward limit of its movement and that by pushing inwardly the button which is at any time outward the locking-plate F will be swung or moved on its pivot.

By reason of the engagement of the detent-arm C' with one of the notches f' f' in the locking-plate it is manifest that so long as no coin is acting thereon the detent-arm C' will be interlocked with the said plate and the same cannot be moved by pushing on either of the push-buttons. When, however, the inner end of the detent-lever C is depressed by the weight of a coin, the detent-arm C' will be raised, the locking-plate F released, and by pressure on the push-button which is at the time extended the same will be forced inward and the locking-plate, with its actuating-arms, swung or turned on its pivot.

The locking-plate F may be connected with any suitable vending or other device which it is desired to actuate. The machine illustrated contains a discharge or delivery apparatus for chewing-gum or candy tablets. The holding device for the articles to be vended embraces two vertical receptacles J J, these being located over the horizontal plate B near the front plate A. Pusher-plates K K slide on the plate B and are attached at their rear ends to the actuating-arms F' F' of the plate F by the studs k k, which slide in slots f' f' in the arms F' F' and which also serve to connect the levers H H with said arms. Said pusher-plates K are shown as provided with parallel slots k', engaging guide-studs k' on the plate B. The forward or outer ends of said pusher-plates K move transversely from front to rear across the bottoms of the receptacles J, which latter are provided with exit-slots at their forward or outer walls, through which tablets contained therein may be pushed by the action of the pusher-plates K K. The exit or delivery passages of the receptacles J are indicated at J' in the drawings. The two pusher-plates K K are so arranged or connected with the actuating-arms F' as to stand one in a retracted and one in an advanced position when the plate F' is locked at one limit of its movement by the detent-arm C', and when said plate F' is moved or actuated by pressure upon one of the push-buttons the retracting pusher-plate K will be advanced and the one which is advanced will be retracted, so that each time the plate F' is actuated a tablet will be ejected from one of the receptacles J.

The machine shown in the drawings is provided with gates adapted to close the exit-passages J' of the vending apparatus. Said gates, as herein shown, consist of sliding plates L, mounted on the rear or inner face of the front plate A and passing through slots l in the top plate B, said plates being connected each with one of the operating-levers

H of the locking-plate F by means of a lever M and a link m, said lever being pivoted to a depending arm M' on the top plate B and being bent or having the form of a bell-crank lever, with its rear end or arm extending upwardly to the point where the link m is connected therewith, so that when the lever H is in the outward limit of its movement and the push-button connected therewith is protruded from the front plate A said plate L will be depressed and when said lever H is pushed backwardly the plate L will be elevated. Manifestly by reason of the connection described the plate L will be depressed as the pusher-plate K advances, so as to open the exit-slot of the receptacle and permit the exit of the tablet which is being pushed therefrom by the pusher-plate. Similarly as the other of the pusher-plates is retracted the plate L at that side of the device will be elevated to close the exit-passage. As the push-buttons in the device described are connected with the actuating-arms F' F' on the actuating-plate F and the said arms are also connected with the pusher-plates of the vending device, it follows that the said arms F' constitute a means of moving both the actuating-plate and the pusher-plates and that said actuating-plate when engaged by the detent-lever C also holds from movement the push-buttons and the pusher-plates. In the construction illustrated, therefore, the push-buttons give movement to the operative parts of the vending device, while the detent-lever, acting on the actuating-plate, may control such movement. Manifestly, however, the actuating-plate F and the push-buttons which are connected and move with the same may be employed to give movement to any other kind of a vending or similar device—as, for instance, similarly-arranged parts may be employed to operate a liquid-vending device, and a construction of this kind is shown in Figs. 4, 5, 6, and 7. In this instance the lever H is extended upwardly from the actuating-plate F and has connected with its upper end a connecting-rod O, which transmits motion, through a lever-arm P', to the turning plug P in a valve-casing Q, said plug and valve-casing constituting a valve by which a measurement of quantities of liquid can be delivered to the spout R of the apparatus. Said valve is arranged to discharge the liquid in two different positions of the valve-plug, which latter is moved into the two different positions referred to by direct connection with the push-buttons of the actuating device, so that whenever either push-button is moved inwardly the valve is brought into position to discharge the liquid from the spout. The valve illustrated is like that shown in my prior patent, No. 611,226, of September 20, 1898, which shows a vending-machine for liquids embracing two measuring-cups in connection with the valve, the parts being so arranged that the valve-plug has two positions, in each of which it permits the

discharge from one receptacle and the filling from the other. In the accompanying drawings the valve casing and plug only are shown, the measuring-cups and liquid-supply devices 5 it being unnecessary to illustrate, because they may be like those shown in my said prior patent. As shown in said drawings, the valve-casing Q is provided with two supply-ports q q', two ports q² q³, located at right angles thereto, and two delivery-ports q⁴ q⁵. Said delivery-ports q⁴ q⁵ are connected by oblique passages with the single pipe Q, which leads to the discharge-spout R. The ports q² q³ communicate with measuring-cups and the 5 supply-ports q q' with a vessel containing the liquid to be furnished or vended. The valve-plug is provided with two ports P¹ P². The port P¹ is so shaped that in one position of the plug it will establish connection between the ports q q' and cut off the exit-port therefrom and in another position of the plug will establish connection between the port q² and the discharge-port q⁴. The port P² is likewise similarly constructed and arranged, but 5 is located at an angle to the port P¹, the angle between the two ports corresponding with the total throw of the valve, so that when the valve is at one limit of its movement the port P¹ will be in communication with one exit- 50 port and when the plug is at the opposite limit of its throw the port P² will be in communication with the other exit-port. As a result of this construction when one of the push-buttons is pushed in it carries the plug to one limit of its movement and brings one of the ports P¹ thereof in communication with the exit-port q⁴ of the valve-casing, while at the same time bringing said port P² into communication with the port q⁵, which is connected with the measuring-cup, so that the liquid in said measuring-cup flows through the exit-port to the discharge-spout, communication with the supply-pipe at this time being closed. When the valve-plug is in this 5 position, the other port P² of the plug will be out of register with the exit-port q⁵, but will be in position to establish connection between the supply-pipe and the measuring-cup, so that the latter will be filling through one of the ports in the plug while the liquid is flowing from the other measuring-cup to the discharge-nozzle. When the other push-button is thrust in, the valve-plug will be reversed and the liquid will pass through the port P² 5 to the discharge-spout and the cup will be filled through the same port.

The main feature of my invention includes in connection with vending mechanism actuating mechanism embracing two push-buttons or manually-operable parts which are mechanically connected with each other, so that when one is thrust inwardly the other will be forced out, so that either one or the other of the push-buttons will always be in its extended position ready for operation. One advantage of a device of this kind is that it requires no spring or springs for the

operation of its parts, but, on the contrary, is entirely positive in its operation, and when shifted into one position it remains in that 75 position until the thrusting in of the other push-button. In a vending mechanism having only one push-button which is returned by a spring the person operating the device must hold the push-button in an inward position against the action of the spring for a sufficiently long time to secure the proper operation of the device, and if this is not done it may fail to properly operate. In the use of the construction illustrated, on the contrary, upon the actuation of one push-button the parts remain in position for the operation of the vending device or discharge of the commodity to be vended until such time as the other push-button is operated, so that the 80 device as a whole is rendered more positive and certain in operation.

The two receptacles shown in Fig. 1, together with the two ejecting-slides, constitute a duplex discharge device, the parts of 90 which are brought alternately into operation by the alternate actuation of the two push-buttons. Likewise in the liquid-vending device shown in Fig. 4 the two sets of valve ports and passages connected therewith constitute a duplex discharge device, the parts of which are brought into position for discharge of the liquid alternately by alternate movement of the push-buttons. This feature of a duplex delivery device for the commodity 95 to be vended is claimed as part of my invention; but I do not desire to be limited to such duplex device, so far as the broader claims are concerned, because a single discharge device may be connected with and operated by 100 two connected push-buttons.

I claim as my invention—

1. The combination with means for delivering a commodity to be vended, of actuating means therefor embracing two manually-operable parts or push-buttons so connected that motion given to one will be communicated to the other.

2. The combination with the wall or casing of a vending mechanism and means for delivering a commodity to be vended, of two push-buttons which extend through the said wall or casing and which are so connected with each other that when one push-button is thrust inwardly, the other will be projected, and operative connections between the said push-button and the delivering means.

3. A vending mechanism embracing two manually-operable members, a pivoted actuating-plate connected with both members and 125 acting to transmit motion from one member to the other, means for delivering a commodity to be vended, and operative connections between the said manually-operable members and the delivering means.

4. A vending mechanism comprising means for delivering an article to be vended, two movable push-buttons, a pivoted actuating-plate, a lever connecting the push-buttons

with the actuating-plate and operative connections between the actuating-plate and the delivering means.

5. A vending device embracing two manually-operable members which are connected and move with each other and a duplex delivering device for the commodity to be vended connected with and operated by said manually-operable members.
10. 6. A vending mechanism comprising two manually-operable actuating members, a pivoted actuating-plate connected with both of said members, a duplex delivering device for the commodity to be vended and operative connections between said delivery means and said manually-operable members.

7. A vending mechanism comprising two manually-operable members, a pivoted actuating-plate connected with both of said members, discharging means for the commodity to be vended connected with and operated by said manually-operable members, and locking means for holding said vending device from operation embracing two notches in said actuating-plate and a detent-lever adapted to engage one of said notches in either position of the plate.

8. The combination of two receptacles for articles to be vended, two sliding ejectors, two manually-operable members or push-buttons, operative connections between said push-buttons by which motion given to one will be communicated to the other, and operative connections between the push-buttons and said sliding ejectors.

35. 9. A vending mechanism comprising two manually-operable actuating members, an

actuating-plate connected with both members, a tilting detent-lever adapted to engage said actuating-plate to hold said manually-operable members from movement, two receptacles for articles to be vended, and ejecting slides in said receptacles, said ejecting slides being connected with and moved by the actuating-plate.

10. The combination of two receptacles for articles to be vended, two sliding ejectors for actuating said ejectors comprising two operable members or push-buttons, sliding gates for closing the exit-openings of receptacles and operative means for operating said sliding gates actuated through movement of the manually-operable members.

11. The combination with two receptacles for articles to be vended, sliding ejectors for actuating said ejectors employing two manually-operable members, sliding gates for closing the exit-openings of receptacles, and operative connections between said sliding gates and the said manually-operable members, whereby said gates are caused to close said exit-apertures when the said ejectors are retracted and are shifted to said exit-apertures when advanced.

In testimony that I claim the foregoing invention I affix my signature, in presence of two witnesses, this 18th day of November, A. D. 1902.
